UNITED STATES PATENT OFFICE.

TAKEBE HASE, OF SAN FRANCISCO, CALIFORNIA.

PROJECTILE.

1,222,288.

Specification of Letters Patent. Patented Apr. 10, 1917.

Application filed October 10, 1916. Serial No. 124,771.

To all whom it may concern:

Be it known that I, TAKEBE HASE, a subject of the Emperor of Japan, residing at the city and county of San Francisco and 5 State of California, have invented new and useful Improvements in Projectiles, of which the following is a specification.

This invention relates to a projectile.

One of the objects of the present invention is to provide a projectile which is especially designed for destroying wire entanglements, aerial crafts, masts, wireless aerials and like structures.

Another object of the invention is to provide a projectile of the character described, which is simple and substantial in construction, and which may be used in conjunction with any standard projectile or gun now in use.

20 Further objects will hereinafter appear.

The invention consists of the parts and the construction and combination of parts as hereinafter more fully described and claimed, having reference to the accompanying drawings in which:—

Figure 1 is a side elevation of the standard form of artillery gun, showing the application of the invention.

Fig. 2 is an enlarged plan partly in section of the gun-barrel, showing the application of the invention.

Fig. 3 is a view similar to Fig. 2 showing the parts still more enlarged.

Fig. 4 is a plan view of the gun-barrel 35 showing the application of the invention.

Fig. 5 is an end view of Fig. 3.

Fig. 6 is a side elevation of a gun barrel showing another form of the invention.

Fig. 7 is an enlarged side elevation of the 40 holder.

Fig. 8 is a detailed section on line 8—8 Fig. 7.

Referring to the drawings in detail, A indicates the carriage of a standard form 45 of artillery gun, 2 the wheels supporting the carriage, 3 the gun barrel proper, and C a projectile which is fired by the gun.

Secured on the outer end of the barrel is a holder which in this instance consists of 50 two semi-circular shaped sections 4 and 5 which are secured together on one side by means of hinges 6 and on the other side by means of flanges 7 and bolts 8. The sections are expanded at 9 to fit the enlarged part of

the outer end 10 of the barrel. The forward end of the holder which consists of the two sections 4 and 5, is tubular in shape, and extends sufficiently far beyond the outer end of the main gun barrel to form a support or holder for the projectile generally indicated at B. This projectile is hollow and its interior diameter is rifled in a manner similar to the interior of the main gun barrel as will hereinafter be described. Formed in the forward end of the projectile 65 is an opening 12 and secured on the forward end of the projectile is a plurality of radially disposed arms 13. Suitably secured in the walls of the projectile rearwardly of the arms 13, is a plurality of spring latches 14, 70 and secured in the hollow sections 4 and 5 is a pair of spring latches 15 which are adapted to secure a projectile when it is inserted or placed in the tubular extension formed by the holder: 75

The head of the main barrel 3 is provided with a breech lock to permit insertion of the projectile C in the usual manner. This projectile when fired is given a turning movement by means of the rifles 16 formed 80 interior of the barrel, the projectile turning or spinning as it leaves the main barrel of the gun, enters the hollow projectile B, and as this is also rifled it can readily be seen that the entering projectile will impart a 85 turning movement to the projectile B which then forms a secondary covering or rider for the projectile C when the two leave the gun barrel in unison.

The strength of the retaining latches 15 is 90 just sufficient to temporarily hold the projectile B against accidental removal or turning movement within the holder, and therefore does not resist or hinder the releasing of said projectile when the main projectile 95 enters. The latches 14 secured in the projectile B snap in behind the main projectile as shown in Figs. 2 and 3, and thus permanently secure the two projectiles together as an integral structure during flight. The 100 radially disposed arms 13 are particularly efficient for destroying wire entanglements such as are used in warfare, and are also very destructive when employed against aerial crafts, masts, wireless aerials and 105 other structures. The spinning or turning movement of the two interlocked projectiles not only cuts through wire entanglements,

but also permits a certain winding action to take place which utterly destroys anything encountered during flight.

The opening 12 formed in the forward end 5 of the projectile B, permits a free escape of the air which is forced out of the barrel the moment the gun is fired. This is an essential feature as any air resistance might possibly force the projectile B out of the holder 10 before the main projectile enters. This is however overcome by providing the opening 12 and the retaining latches 15.

For the purpose of permitting a perfect alignment of the rifling in the projectile B 15 with relation to the rifling in the main gun barrel 3, a very simple mechanism has been employed. A mark or a line 18 either existing or placed on the main barrel, permits the sections 4 and 5 of the holder when applied, 20 to be placed in such a position that the hinges 6 will line up with same, the retaining latches 15 being permanently secured and fitting in depressions formed on the exterior surface of the projectile B, and 25 will then assume such a position that when the projectile is inserted, a positive register between the rifle of both members is secured.

By referring to Fig. 6 it will be seen that 30 another form of the holder is employed. This is necessary where the outer end of the main barrel 3 is not enlarged as shown at 10, Fig. 2. Where straight barrels of the shape shown in Fig. 6 are employed, it is 35 not necessary to enlarge the holder sections as indicated at 9. It therefore becomes necessary to secure the holder against endwise movement, that is, from being blown off the end of the barrel when the gun is 40 fired. This is accomplished by providing a pair of eye-bolts 20 and chains 21, which may be secured to the pintles 22 by which the main barrel is supported. This simple 45 mechanism positively secures the holder against accidental removal either when firing the gun or otherwise, and does not interfere with the operation of the gun employed.

The whole mechanism, that is the holder 50 together with the projectile B, may be attached practically speaking to any form of gun, although it is preferably used with portable artillery, and it is obvious that it may be attached to naval guns as well as 55 other types.

The materials and finish of the several parts of the device may otherwise be such as the experience and judgment of the manufacturer may dictate.

60 I wish it understood that various changes in form, proportions and minor details of construction may be resorted to within the scope of the appended claims, and that I do not wish to limit myself to the specific design or construction here shown.

Having thus described my invention, what I claim and desire to secure by Letters Patent is:—

1. The combination with the barrel of a gun and the projectile which is adapted to be discharged by the gun, of a holder secured on the outer end of the barrel, a hollow separate rider projectile supported by the holder in alignment with the muzzle of the barrel, rifles formed interior of the rider projectile, means for insuring a positive alignment of said rifling with relation to the rifling in the gun barrel, and means for temporarily securing said rider projectile against turning and endwise movement when inserted in the holder. 70

2. The combination with the barrel of a gun and the projectile which is adapted to be discharged by the gun, of a holder secured on the outer end of the barrel, a hollow separate rider projectile supported by the holder in alignment with the muzzle of the barrel, rifles formed interior of the rider projectile, means for insuring a positive alignment of said rifling with relation to the rifling in the gun barrel, means for temporarily securing said rider projectile against turning and endwise movement when inserted in the holder, a plurality of radially disposed arms on the rider projectile, and latch members on said projectile adapted to lock the main projectile against removal after it has entered. 85

3. In combination with a gun barrel, a rider projectile, means to secure said rider projectile to the outer end of the barrel, and means connected to the rider projectile and engageable with the periphery of the fired projectile and over the rear end wall of the fired projectile for anchoring the rider to the fired projectile. 100

4. In combination with a gun barrel, a rider projectile formed hollow to receive the fired projectile therein, a holder for securing the rider to the barrel, and means borne by the rider and located outwardly beyond the interior of the rider and having parts extending inwardly thereof to engage over the rear end of the fired projectile to lock the rider thereto. 110

5. In combination with a gun barrel, a rider projectile formed hollow to receive the fired projectile therein, a holder for securing the rider to the barrel, and spring arms secured to the rider outwardly beyond the interior thereof and having parts projecting within the rider interior to engage over the rear end of the fired projectile to lock the rider thereto. 120

6. In combination with a rifled gun barrel, a hollow rifled rider projectile, a holder for the rider, means for insuring a positive alignment of the rider rifling with that of the gun barrel, and means to lock the rider to the fired projectile. 125

7. In combination with a rifled gun barrel, a hollow rifled rider projectile, and means to secure the rider to the barrel whereby the fired projectile will enter the 5 rider and turn the latter.

8. In combination with a gun barrel, a rider projectile, a holder for the rider, means to anchor the rider to the fired projectile, and spring pressed means carried by the 10 holder for engaging the rider to hold same, said means being automatically displaced by engagement with the rider to allow the latter to be inserted in the holder.

9. In combination with a gun barrel, a

hollow rider formed to receive the fired 15 projectile therein and having an opening in its front part to receive the nose of the projectile, and means to engage the rear end wall of the fired projectile to thereby positively hold said nose in its said engagement 20 with the front part of the rider.

In testimony whereof I have hereunto set my hand in the presence of two subscribing witnesses.

TAKEBE HASE.
